DESIGN FOR A SPINNING WHEEL AMUSEMFNT DEVICE

James P. Harrison, Jr., Waco, Tex.

Application October 3, 1935, Serial No. 58,827

Term of patent 7 years

To all whom it may concern.

Be it known that I, James P. Harrison, Jr., a citizen of the United States, residing at Waco, in the county of McLennan and State of Texas, have invented a new, original and ornamental Design for a Spinning Wheel Amusement Device, of which the following is a specification, reference being had to the accompanying drawing, forming part thereof.

The single figure is a front elevational view of

a spinning wheel amusement device showing my new design.

The rear of the device is plain and flat and undecorated, while the opposite side of the bench portion is exactly the same as the front thereof shown in the view.

I claim:—

The ornamental design for a spinning wheel amusement device, as shown and described.

JAMES P. HARRISON, JR.
